(57) **CLAIM**

The ornamental design for an ice maker, as shown and described.

DESCRIPTION

FIG. 1 is a perspective view of a first embodiment of an ice maker;

FIG. 2 is a front view thereof;

FIG. 3 is a right side view thereof;

FIG. 4 is a top view thereof;

FIG. 5 is a perspective view of a second embodiment of an ice maker;

FIG. 6 is a front view thereof;

FIG. 7 is a left side view thereof;

FIG. 8 is a top view thereof;

FIG. 9 is a perspective view of a third embodiment of an ice maker;

FIG. 10 is a right side view thereof;

FIG. 11 is a perspective view of a fourth embodiment of an ice maker; and,

FIG. 12 is a left side view thereof.

The rear and bottom of the ice maker form no part of the claimed design.

In the first and third embodiments, the left side of the ice maker forms no part of the claimed design.

In the second and fourth embodiments, the right side of the ice maker forms no part of the claimed design.

In the third and fourth embodiments, the top of the ice maker forms no part of the claimed design.

The unevenly broken lines depict unclaimed boundary of the claim; the evenly broken lines depict unclaimed portions of the ice maker only. The broken lines form no part of the claimed design.

1 Claim, 12 Drawing Sheets
